UNITED STATES PATENT OFFICE.

ALFRED EVRARD, OF PARIS, FRANCE.

APPARATUS FOR AUTOMATICALLY LOWERING ARTICLES AND CHECK FOR SPEED.

SPECIFICATION forming part of Letters Patent No. 416,159, dated December 3, 1889.

Application filed April 19, 1889. Serial No. 307,900. (No model.) Patented in France November 23, 1887, No. 187,788; in Belgium February 7, 1888, No. 80,556, and in England February 10, 1888, No. 2,044.

To all whom it may concern:

Be it known that I, ALFRED EVRARD, a citizen of the French Republic, residing at Paris, France, have invented a new and useful Apparatus for Automatically Lowering Packages, Bales, or other Articles, and a Check for Regulating the Speed of Same, (for which I have obtained Letters Patent in France, No. 187,788, dated November 23, 1887; in Great Britain, No. 2,044, dated February 10, 1888, and in Belgium, No. 80,556, dated February 7, 1888;) and I do hereby declare that the following is a full, clear, and exact description of the same.

My invention has for its object an automatic or self-acting apparatus for lowering articles, together with a check for regulating the speed of same; and it consists, essentially, in the combination of a resisting steel ribbon whereto the burden which is to be lowered is attached, with a spool whereon the ribbon is attached and rolled, which spool is provided with a screw-shaped toothed wheel gearing with a worm mounted on a common axle, with a self-acting regulating brake or check formed by a system of small heavy bodies interlocated between the arms of a frame, which, being on the same axle with the worm, is of course carried along in its rotary motion, thereby pushing the said bodies by centrifugal force against the inside surface of the box wherein the system is contained.

In the annexed drawings, Figure 1 shows an exterior view of the apparatus; Fig. 2, a sectional view on the line *a b* of Fig. 1; Fig. 3, a sectional view on the line *c d e f* of Fig. 2; Fig. 4, a sectional view on the line *g h* of Fig. 3. Figs. 5, 6, and 7 show details of some parts of the apparatus.

Similar letters of reference refer to similar parts throughout the several views.

The apparatus is composed of a spool *A*, whereon is rolled a ribbon of laminated steel *B*, with a capability of carrying one hundred and fifty kilograms per square millimeter in section, which may be readily obtained at the present state of metallurgy. This ribbon is attached to the central part of the spool, which is allowed to revolve in a casing *D*, wherein it is held by means of its hollow pivots *D'*.

The spool *A* carries at one side on its exterior periphery a screw-shaped toothed wheel *A'*, which gears with a worm *E*, on the axle *E'* of which worm is mounted a frame *F*, 55 lodged in a cylindric casing *G*, formed in one with the casing or box *D*. Six (more or less) small but heavy bodies in sector shape *H* are loosely intercalated in the arms of the frame *F*.

The apparatus being secured to a stationary point by means of the ring *L*, and the articles which are to be lowered being suspended to the ring *L'*, the ribbon will roll off under the strain of the weight of the article, 65 and will thereby carry along the spool, which brings the worm *E* and the intercalated bodies *H* into motion. These bodies are by the working of centrifugal force pushed against the inside walls of the casing *G*, and produce 70

a friction in proportion to the square of the speed of descent of the article. From the commencement of the lowering the speed of the descent is regulated by the check or frame operating, as above described, in proportion with its dimensions. The ribbon having been rolled off, the apparatus must be brought back into working position, and for this purpose the worm *E* must be taken out of gear with regard to the screw-shaped 75 toothed wheel *A'*, so as to allow the steel ribbon to be wound up again. For this purpose the lid *I*, closing the casing *G*, is provided

with a disk *I'*, Figs. 3 and 7, wherein an opening *I²* is arranged, through which opening the 85 axle *I³* of the worm passes, so as to disengage the screw-shaped toothed wheel *A'*. In order to bring the opening *I²* over the axle *I³*, it is sufficient to revolve the disk *I'* on the screw *i*. The axle *I³* is then projected and 90 consequently the worm *E* taken out of gear. This done, the crank *m*, pivoted at *m'* on the spool *A*, is turned outward, and by means of this crank the ribbon is again rolled on the spool in the same manner as is done with a 95 tape-measure. As soon as the ribbon is entirely rolled on the spool the axle *I³*, and in connection therewith the worm *E*, is pushed back to its place and consequently thrown into gear again. The disk *I'* is revolved in 100 an inverse direction on the screw *i*, so as to steady and hold from endwise movement the

axle I^3 of the worm, whereupon the small crank m is turned again inward to take the position shown in Fig. 2, whereby its knob m^2 is held in place by the plate-spring n , where-
5 in a hole n' is arranged, as shown in Fig. 5. The apparatus is then put back to a place ready for use.

What I claim is—

1. In an automatic apparatus for lowering articles, the combination of a spool, a suspension-ribbon or its equivalent wound thereon and attached thereto, a rotary shaft geared with said spool, a frame carried by said shaft, a casing surrounding said frame, and a heavy body loose within the casing engaged by said frame and adapted to be thrown into frictional contact with the inner peripheral surface of said casing by the revolution of said shaft, substantially as set forth.
- 10 2. In an automatic apparatus for lowering articles, the combination of a spool having a worm-wheel, a suspension-ribbon or its equivalent wound thereon and attached thereto, a rotary shaft and worm engaging said wheel, a frame carried by said shaft, a casing surrounding said frame, and a heavy body en-

gaged by said frame, and within and adapted to be thrown into frictional contact with said casing by the revolution of said shaft, said shaft being bodily movable to disengage it 30 from the worm to allow of the winding up of the ribbon, substantially as set forth.

3. In an automatic apparatus for lowering articles, the combination of a spool, a suspension-ribbon or its equivalent wound thereon, a rotary shaft geared with said spool, a frame carried by said shaft, a casing surrounding said frame, and a heavy body engaged by said frame, and within and adapted to be thrown into frictional contact with said 35 casing by the revolution of said shaft, said casing having an end aperture and movable cover or disk for permitting the end movement of said shaft and worm to disengage the latter from the spool, substantially as set 40 forth.

In witness whereof I have hereunto set my hand in presence of two witnesses.

ALFRED EVRARD.

Witnesses:

LOUIS TROTTIER,
JULES DAYOLLET.
